United States Patent Office

Des. 189,581
Patented Jan. 10, 1961

189,581

PLAYGROUND GYM STRUCTURE

Ralph E. Williams and Warren P. Miller, Anderson,
Ind., assignors to American Playground Device Co.,
Anderson, Ind., a corporation of Indiana

Filed July 12, 1960, Ser. No. 61,306

Term of patent 14 years

(Cl. D34—5)

Fig. 3

Fig. 1 is a front perspective view of a playground gym structure showing our new design; Fig. 2 is a top plan view thereof; and Fig. 3 is a rear elevational view thereof.

We claim:

The ornamental design for a playground gym structure, as shown.
